UNITED STATES PATENT OFFICE.

SAMUEL W. BELK, OF WALLINGFORD, CONNECTICUT, ASSIGNOR TO SIMPSON, HALL, MILLER & CO., OF SAME PLACE.

DESIGN FOR A HANDLE FOR A SPOON OR FORK.

SPECIFICATION forming part of Design No. 12,330, dated June 28, 1881.

Application filed May 17, 1881. Term of patent 7 years

To all whom it may concern:

Be it known that I, SAMUEL W. BELK, a citizen of the United States, residing at Wallingford, in the county of New Haven and State of Connecticut, have invented and produced a new and original Design for the Handle of Spoons, Forks, and Similar Articles, of which the following is a specification, reference being had to the accompanying drawing, forming part thereof, in which is represented a front view of a spoon having my newly-designed handle.

The invention relates to a design for the handle of spoons, forks, and like articles of table service; and it consists in the peculiar Gothic configuration of the central inclosure formed by the fillets on each side thereof, with a handle having a semicircular tip, in connection with the representation of a fan-shaped design within said tip and the representation of a series of stars arranged in small panels in a line across the handle at the top of the Gothic-arch configuration.

It consists, also, in the representation upon the central boss of the handle of two series of parallel lines or ribs, one series being parallel with the axis of the handle and the other at an angle of forty-five degrees therewith, in connection with a segmental representation above said boss, and flowering plants above the latter and within the lower portion of the Gothic arch above mentioned.

Heretofore spoon and fork handles have been made with a semicircular tip, and also provided with designs representing a fan or fan-shaped configurations, as well as with central inclosures of various forms, and flowering plants within them; but my design differs in many respects from all made previously.

To describe the invention more fully: Starting from the body of the article, the handle is provided nearly half-way of its length (according to the article) with a boss or square panel,

a, having thereupon two series of projecting lines or ribs, one series being parallel with the axis of the handle and the other at an angle of forty-five degrees to the first. Above this panel *a* is a segmental panel, *b*, and standing upon the curved top of the latter are flowering plants *c*, within a blank panel, *d*, having the form of a Gothic arch, produced by the inner fillets, *d'*, meeting at the central point or apex, *e*. Above this apex *e* the fillets diverge again and form, with the semicircular tip of the handle, a fan-shaped configuration, *f*, having a series of segmental panels inclosing various ornaments. Across the upper portion of the handle and passing at the apex of the central Gothic arch is a fillet-line, forming the upper limit of two small panels, *g*, each one inclosing three stars, and under the small panels *g* are two triangular panels containing a leafy branch, altogether bringing the central Gothic arch in clear relief.

I claim—

1. The herein-described design for articles of table service, consisting of a handle having a semicircular tip, and provided with fillets forming a Gothic arch in the center, and diverging to form a fan-shaped configuration above the apex of said arch, with two small panels across the upper end of the handle and in line with the top of said arch, substantially as shown and described.

2. The design for articles of table service, consisting of a handle having a boss or square panel, *a*, provided with longitudinal and diagonal lines, arranged as described, a segmental panel, *b*, and flowering plants *c*, standing upon the curved top of the latter panel and within the lower portion of the Gothic arch, substantially as shown and described.

SAMUEL W. BELK.
